US00D449360B1

(12) United States Design Patent **(10) Patent No.:** **US D449,360 S**
Kallassy **(45) Date of Patent:** **** Oct. 16, 2001**

---

(54) GOLF SWING TRAINING DEVICE

4,511,147 4/1985 Olsen .
5,377,984 1/1995 Ciccia .

(76) Inventor: **Charles Kallassy**, 4074 S. Better Dr.,
Dallas, TX (US) 75229

* cited by examiner

(**) Term: **14 Years**

Primary Examiner—Mitchell Siegel
(74) Attorney, Agent, or Firm—Darby & Darby

(21) Appl. No.: **29/118,139**

(57) CLAIM

(22) Filed: **Feb. 2, 2000**

The ornamental design for a golf swing training device, as shown.

(51) LOC (7) Cl. **21-02**

DESCRIPTION

(52) U.S. Cl. **D21/758**

(58) Field of Search **D21/756, 758;**
473/300-303, 201, 203
